MINING MACHINE

Original Filed Jan. 13, 1922 2 Sheets-Sheet 2

UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed January 13, 1922, Serial No. 529,068. Renewed June 3, 1929.

My invention relates to mining machines. It has for its object to provide an improved mining machine, and, more particularly to provide an improved feeding mechanism for such a machine, whereby the feeding operation is facilitated and the feeding mechanism is simplified and rendered more flexible at the same time that the cost of the same is materially reduced. A further object of my invention is to provide an improved lateral feeding mechanism and one which is equally adapted to feed to the right or left. These and other objects and advantages of my improvement will, however, hereinafter more fully appear.

Although it should be understood that certain features of my invention if desired may be utilized in connection with other types of machines than that shown for illustrative purposes, I have shown in the accompanying drawings, one embodiment which my invention may assume in practice, illustrating the same as applied to a mining machine of the room-and-pillar type.

25 In these drawings:—

Fig 1 is a plan view of a machine embodying the illustrative form of the invention, showing the same applied to a cable propelled machine utilizing a plurality of cables, portions of the casing being broken away and certain parts of the mechanism being shown in longitudinal section, to facilitate illustration.

Fig. 2 is a side elevation of the machine shown in Fig. 1, certain parts also being similarly broken away or shown in section to facilitate illustration.

Fig. 3 is a diagrammatic plan view showing the machine of Figures 1 and 2 in different positions during its cutting operations.

40 In these figures it will be observed that the mining machine comprises a machine frame 1 slideable on its bottom 2 on the mine bottom, and carrying a cutter bar 3 which as usual in a room-and-pillar machine projects in a horizontal plane from the front end of the machine and carries a cutter chain 4 movable about the bar by means of a cutter chain driving sprocket 5 carried on the frame 1 and herein disposed beneath the same at 45 a point slightly nearer the rear end thereof.

This cutter chain driving sprocket 5 is herein driven, through connections hereinafter described, from a suitable motor 6 carried on the frame, herein a longitudinally disposed horizontal electric motor carried on the front end of the frame. As shown, the frame also carries feed operating and controlling mechanism in the form of controlling and feeding drums 7 and 8 adapted to cooperate with flexible feeding portions 9 and 10, herein in the form of separate cables wound on the drums, and driving connections between the drums and the motor, hereinafter described, whereby when the flexible feeding portions are extended from the drums to the right and left hand ribs in the mine and suitable guiding mechanism, in the form of sheaves 11 and 12, is provided at the diagonally opposite corners of the frame, means are provided to direct the cutting mechanism laterally across a mine face.

Referring more particularly to this construction it will be observed that the rear end of armature shaft of the motor 6 carries a bevel pinion 13 meshing with a larger bevel gear 14 carried on an upright shaft 15 suitably journaled at 16 on bearings on the frame 1, and that this shaft 15 carries on its lower end a spur pinion 17 meshing with a larger spur gear 18 which is as usual operatively connected through suitable clutch mechanism (not shown) to the cutter chain driving sprocket 5. Obviously through the driving train just described the cutter chain 4 may be driven by the motor whenever it is desired and, through the reduction gearing provided, driven at the desired cutter chain speed, although it will be understood that through modification of the drive train the speed of the cutter chain drive may be varied if desired.

Operatively connected to the gear 18 and rotatable thereby is a train of mechanism driving the feeding mechanism. As shown, this mechanism includes an upright shaft 19 suitably journaled as at 20 on the frame 1 and carrying on its upper end a bevel pinion 21 which in turn meshes with a larger bevel 22 carried on a longitudinally disposed shaft 23. Herein the gear 22 is adapted to be con-

55.

nected to the shaft 23 through a friction clutch 24 having one element 25 fixed to the shaft as at 26 and the other element movable longitudinally of the shaft and pressed into and 5 out of driving relation with its fellow by means of a clutch shipper 28 controlled by a suitable controlling member 29, herein on the upper surface of the frame 1. As shown, this shaft 23 is suitably journaled in bearings 10 30 on the frame and carries near its rear end a worm 31 which meshes with a worm gear 32 disposed on a transverse axis beneath the worm and carrying within a casing 33 a usual differential mechanism including rotatable bevel pinions 34, 35 rotatable about intersecting axes and cooperating larger pinions 36, 37 coaxial with the worm gear and meshing with the pinions 34, 35 in a usual manner. As shown the differential casing 33 15 20 is journaled in suitable bearings 38, 39 carried on the frame and the gears 36 and 37 are fixed to the ends of transversely disposed oppositely extending feed driving shafts 40 and 41, herein through being carried on portions of polygonal section 42, 43 formed near the adjacent ends of said shafts, while the shafts carry on their adjacent ends cooperating abutting portions 44, 45 of reduced cross section which herein extend through the 25 30 usual yoke 46 on which the pinions 34 and 35 are rotatably mounted.

From the differential, connection is made to each of the controlling and feeding drums 7 and 8. As shown, the outer end of the shaft 35 41 is journaled on the frame 1 as at 47 and connected to the feed drum 8 by a pinion 48 on the free end of the shaft which extends beyond the frame 1 and there meshes with an internal gear 49 carried on the drum, the 40 drive connection herein being made to the drum at a point in rear of the drum bearing 50, while the rotation of the shaft is controlled by a friction member 51 fixed at 52 to the shaft and adapted to have its rotation 45 controlled by a brake band 53 of usual form controllable by a controlling member 54 operable from the rear end of the frame. The other shaft 40 is similarly journaled at 55 and connected to the controlling drum 7 through 50 a spur pinion 56 and an internal gear 57 and is similarly controlled through a friction member 58 fixed at 59 to the shaft and having its rotation controlled by a brake band 60, in turn controllable through a controlling 55 member 61, likewise operable from the rear end of the frame. By this mechanism it will be observed that it is possible to drive both of the drums 7, 8 at a slow or cutting speed, power being normally transmitted to both drums 60 in the usual manner. Further, the rotation of either of the drums and the resultant operation of the differential is controllable at will through control of the controlling members 54 and 61.

65 I have found that in lieu of the friction

members 51 and 58, the peripheries of the drums 7 and 8 may be utilized as friction members if desired, the same being provided as at 51' and 58' with friction surfaces and having cooperating brake bands 53'' and 60' 70 operable by controlling members 54'' and 61''. Such a construction simplifies a machine of the character so far described and provides an excellent friction device.

Cooperating with this mechanism is also 75 improved mechanism for driving the shafts 40 and 41 at a higher speed. This mechanism herein drives the shaft 23 and is connected between the same and the armature shaft, the same including a spur pinion 62 on that shaft in front of bevel pinion 13, which pinion 62 in turn meshes with a larger spur pinion 63 carried on an independent stub shaft 64, herein disposed above the motor armature and in alinement with the shaft 23. As shown, one end of this shaft 64 is carried by the motor casing and the other end keyed as at 65 to a sleeve 66 on one member 67 of a friction clutch 68, the other member 69 of which is keyed as at 70 to the end of the shaft 23 and is adapted to be forced into clutching relation with its fellow by means of the clutch shipper 28. It will also be noted that the two shafts 64 and 23 abut one against the other in a suitable manner, a reduced portion 71 90 on the shaft 23 being rotatable in a bore or bearing 72 in the adjacent end of the shaft 64. By this mechanism it will be observed that it is possible, whenever desired, to drive the shaft 23 directly from the motor and at a 95 relatively high speed by connecting the clutch 68 and that this connection automatically disconnects the clutch 24 so that the slow speed feed train connected to the bevel gear 21 is rendered automatically inoperative. Similarly it will be observed that when the member 28 is operated to connect the clutch 24 and thereby throw in the slow speed train, the clutch 68 will be released in such a manner as 100 automatically to disconnect the high speed feed train including the gears 62, 63.

In the operation of my improved mechanism above described it will be observed 105 that it is possible to drive the feeding mechanism through the differential and thereby to rotate both the drums 7 and 8 at the same speed if desired, the feed drum 8 then acting to draw in the advance flexible feeding member 10 at the same rate that the controlling drum 7 acts to pay out the flexible feeding member 9 on the receding side of the frame. It will also be observed that the differential mechanism will act to drive these drums at different speeds in accordance with the speeds of the shafts 40, 41, so that when 110 needed the drum 8, for example, may rotate faster than the drum 7, or vice versa. Thus, through the controlling brake bands 53, 60 it is possible to vary the effect of the feed 115 as desired, an application of the brake band 120

70

130

60 causing the speed of the shaft 40 to be reduced and thereby causing an increase in speed of the shaft 41, while the application of the brake band 53 causes the speed of the shaft 41 to be reduced and thereby causes the speed of the shaft 40 to be increased. Thus, it will be evident that by adjusting one or the other of these brake bands it is made possible for the machine to be fed either way or angled as desired. It will also be evident that the features above described including the differential drive and the control by the brake bands, will apply equally as well when the machine is driven at a slow 10 or cutting speed through the train including the bevel pinion 21 as when the machine is driven through the fast feed including the gears 62, 63. It will also be observed that through the frictions 24 and 68 breakage of either mechanism is prevented at the same 20 time that the operator is enabled through slipping of these frictions to vary the control if desired. Attention is also directed to the fact that with my improved mechanism 25 the machine may be sumped into the face, moved transversely thereof, and withdrawn at the opposite rib without interrupting its movement. It will also be noted that by reversing the sheaves 11 and 12, with or without 30 their supports, or by providing a second set of guide sheaves 11', 12' disposed at the corners of the frame unoccupied by the sheaves 11 and 12 heretofore described, the machine may be readily adapted at any time 35 to cut either to the right or to the left, i. e. from the right hand rib to the left hand rib, or from the left hand rib to the right hand rib as desired, either of the drums 7 and 8 thru my improved mechanism being 40 equally adapted to use as a feed operating member or as a controlling member. It will of course be obvious that when the front 45 guide sheave 12' is to be used when the cable 9 passes over the top of the drum 7, the sheave will be disposed at a suitable angle to receive the cable.

Attention is directed to the fact that as a result of my improved mechanism an intermediate feed is provided which is adapted to use in sumping, this feed being obtained by tightening one of the members 53, 60 so as to hold its shaft still and letting all of the rotation be taken on the other shaft which will then rotate at twice its normal 55 speed and thereby provide a feed intermediate the slow and fast feed and especially adapted for use in sumping. It should also be observed that through the use of my improved construction, automatic compensating mechanism is provided during angling the machine, as for instance, when angling in a cut, the differential mechanism operating when one feed is increased, as for instance, when the speed of rotation of the 60 controlling drum 7 is increased, automatically 65

ly to reduce the other feed, as for instance the forward feed, and thereby, as distinguished from the forward feed, continuing to feed the bar forward while the takeup is operating, automatically cutting down the feed of the bar in proportion to the increased speed of the controlling drum 7.

As a result of my improvement it will also be observed that not only is the feeding mechanism materially simplified and cheapened but at the same time the same is rendered fool-proof so that it may not be damaged by even the most ignorant operator. It should also be observed that these results are obtained without any necessity for operating a plurality of clutches in a predetermined sequence which must be maintained in order to prevent breakage, the only clutch in my improved machine being capable of being operated at any time without damage to the machine while the friction bands may be similarly operated either alone or in combination with the clutch.

While I have in this application specifically described one form which my invention may assume in practice, it will be understood that, while this form has been chosen for purposes of illustration, the invention may be modified and used in different forms or applied to machines of different types without departing from the spirit of the invention and that it is my intent to include these other embodiments within the scope of the appended claims.

What I claim as new and desire to secure by Letters Patent is:

1. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame and controlling means therefor including relative rotatable feed operating and controlling members cooperating one with each of said portions, differential gearing operatively connected to said members for effecting simultaneous rotation thereof at equal rates in the same direction, and driving connections between said motor and said differential gearing.

2. The combination with a mining machine, of a controlling member adapted to cooperate directly with a flexible feeding element in controlling machine movement, a motor, a differential operatively connected with the motor and having a plurality of master

gears and a common gear meshing therewith, and a driving connection between the differential and the controlling member whereby the speed of the latter may be varied while the motor speed remains constant.

3. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame and a plurality of relatively rotatable feed operating and controlling members co-operating respectively therewith, and driving mechanism therefor including a differential having corresponding elements operatively connected to the feed operating and controlling members.

4. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a differential, relatively rotatable feed operating and controlling members connected to different elements of said differential and respectively operatively connected to said portions, and means controlling the rotation of said members.

5. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a differential, relatively rotatable feed operating and controlling members connected to different elements of said differential and respectively operatively connected to said

portions, and means for retarding either of said members.

6. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a differential, a plurality of shafts connected to different elements of the latter, and relatively rotatable feed operating and controlling members driven one by each of said shafts and respectively cooperating with said portions.

7. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a differential, a plurality of shafts connected to different elements of the latter, relatively rotatable feed operating and controlling members driven one by each of said shafts and respectively cooperating with said portions, and means controlling the rotation of said shafts.

8. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members respectively cooperating directly with said portions and operating mechanism therefor including a differential, and means for bodily driving said differential at a plurality of speeds while said motor speed remains constant.

9. A mining machine slidable on a mine

bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members respectively cooperating directly with said portions and operating mechanism therefor including a differential, and means for driving said differential at a plurality of speeds including a plurality of driving trains.

10. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members respectively cooperating directly with said portions and operating mechanism therefor including a differential, and means for driving said differential at a plurality of speeds including a plurality of driving trains and a clutch mechanism operative to connect one train and disconnect the other.

11. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members respectively cooperating directly with said portions and operating mechanism therefor including a differential, and means for driving said differential at a plurality of speeds including a plurality of driving trains and a single frictional mech-

anism operative to connect or control either train.

12. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members respectively cooperating directly with said portions and operating mechanism therefor including a differential connected to said feed operating means, and frictional means controlling the rotation of said feed operating means.

13. The combination with a mining machine, of cutting mechanism, feed operating mechanism including relatively rotatable feed operating and controlling members together controlling the rate of feed and the direction of said machine as a whole and means for rotating said members either simultaneously at speeds which vary in inverse ratio, or separately, including a differential, and means for driving said differential at different speeds including a train driven from said cutting mechanism and a train independent of said cutting mechanism.

14. The combination with a mining machine, of cutting mechanism, feed operating mechanism including relatively rotatable feed operating and controlling members together controlling the rate of feed and the direction of said machine as a whole and means for rotating said members either simultaneously at speeds which vary in inverse ratio, or separately, including a differential, and means for driving said differential at different speeds including a train driven from said cutting mechanism and a high speed train independent of said cutting mechanism.

15. The combination with a mining machine, of cutting mechanism, feed operating mechanism including relatively rotatable feed operating and controlling members together controlling the rate of feed and the direction of said machine as a whole and means for rotating said members either simultaneously at speeds which vary in inverse ratio, or separately, including a differential, and means for driving said differential at different speeds including a train driven from said cutting mechanism and a high speed train independent of said cutting mechanism and a friction mechanism controlling both trains.

16. A mining machine slidable on a mine

bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame and feed operating and controlling means cooperating with said portions including a differential, worm and worm gearing driving mechanism therefor operable by said motor, and means for rotating said worm at different speeds while said motor speed remains constant.

17. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame and feed operating and controlling means cooperating with said portions including a differential, worm and worm gearing driving mechanism therefore operable by said motor, and means for rotating said worm at different speeds including a plurality of drive trains.

18. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members on opposite sides of said frame cooperating with said portions, driving mechanism therefor including a differential, oppositely disposed shafts connected to the latter and to said members, and means for controlling the rotation of said feed operating and controlling members.

19. A mining machine slidable on a mine bottom during cutting comprising a frame,

cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members on opposite sides of said frame cooperating with said portions, driving mechanism therefor including a differential, oppositely disposed shafts connected to the latter and to said members, and independently operable friction means for controlling the rotation of said shafts.

20. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a feed operating member and a relatively rotatable controlling member cooperating with said portions, and means whereby during concurrent operation the former may be retarded while the speed of the latter is correspondingly increased.

21. A mining machine slidable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, relatively rotatable feed operating and controlling members cooperating with said portions, and means for driving the same whereby the speeds may vary in inverse proportion.

22. A mining machine slidable on a mine bottom during cutting comprising a frame, cutting mechanism supported thereby including a cutter bar projecting from said frame in fixed angular relation thereto whereby the angle of said cutting mechanism to the work-

- ing face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a feed operating member and a relatively rotatable controlling member ¹⁰ cooperating with said portions, and means automatically operative upon retardation of one member to increase the speed of operation of the other.
23. A mining machine slideable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a feed operating member and a relatively rotatable controlling member ²⁰ cooperating with said portions, and means automatically operative upon retardation of either member to increase the speed of the other.
24. A mining machine slideable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a feed operating member and a relatively rotatable controlling member ³⁰ cooperating with said portions, and means automatically operative upon retardation of either member to increase the speed of the other.
25. A mining machine slideable on a mine bottom during cutting comprising a frame, cutting mechanism supported thereby including a cutter bar projecting from said frame in fixed angular relation thereto whereby the angle of said cutting mechanism to the working face is determined by the angle of said frame to the face, a motor, and means operated thereby for effecting bodily lateral feeding movement of said machine and determining the angle of the machine including advance and receding flexible feeding portions disposable laterally in opposite directions from points adjacent the opposite ends of the frame, a feed operating member and a relatively rotatable controlling member ⁴⁰ cooperating with said portions, and means automatically operative upon an increase in speed of said controlling member to decrease the speed of said feed operating member.
26. The combination with a mining machine having cutting mechanism, of a feed operating member therefor adapted to cooperate with flexible means extending in advance of the machine in effecting lateral feeding during the cutting operation, worm gearing ⁵⁰ for driving the same, and a plurality of independently operable friction means adapted to control rotation of said member.
27. The combination with a mining machine, of a feed operating member adapted ⁶⁰ to cooperate with flexible means in effecting lateral feeding, means for driving the same including worm gearing, and a plurality of independently operable friction controlled means each adapted to effect a different speed ⁷⁰ of said feed operating member.
28. The combination with a mining machine, of a feed operating member adapted to cooperate with flexible means in effecting lateral feeding, means for driving the same including worm gearing, and a plurality of independently operable friction controlled means disposed on opposite sides of said worm gearing for controlling said member.
29. The combination with a mining machine, of a plurality of relatively rotatable feed operating and controlling members adapted to cooperate with flexible means in effecting lateral feeding, driving mechanism therefor including worm gearing, and a plurality ¹⁰⁰ of friction controlled means each adapted to control both of said feed operating and controlling members.
30. The combination with a mining machine having cutting mechanism, of a feed ¹¹⁰ operating member adapted to cooperate with flexible means extending in advance of the machine in effecting lateral feeding during the cutting operation, and driving mechanism therefor including a plurality of parallel shafts, worm gearing driven thereby and operatively connected to said feed operating member, and a plurality of friction controlled means disposed in the driving connections between said worm gearing and feed ¹¹⁵ operating member.
31. The combination with a mining machine, of a feed operating member adapted to cooperate directly with flexible feeding means, and driving mechanism therefor including a plurality of vertically disposed substantially parallel shafts, means for driving one of said shafts through the other including a motor, worm gearing associated with said shafts, and a plurality of frictionally con- ¹²⁵ ¹³⁰

trolled means disposed between said vertical shafts and feed operating member.

32. The combination with a mining machine, of a plurality of relatively rotatable feed operating and controlling members rotatable about horizontal axes extending in the same general directions and each adapted to cooperate directly with flexible feeding means, separate shafts associated with each 10 of said members and whose axes also extend in the same directions as the axes of said members, driving mechanism for said members including worm gearing associated with said shafts at substantially the ends thereof, and 15 a plurality of frictionally controlled means associated with said shafts and disposed between the worm gearing and said members.

33. In a mining machine, a machine frame 20 slideable on its bottom on the mine bottom, a motor carried thereby, and feeding mechanism driven by said motor including a plural speed transmission mechanism including coaxial gears rotatable on an axis extending longitudinally of the machine, a clutch member 25 coaxial with said gears and movable horizontally in opposite directions to effect different speeds, and a single terminal element through which all speeds are transmitted arranged coaxially with said gears, 30 and a plurality of relatively rotatable feed operating and controlling members driven by said transmission mechanism through said gears and each adapted to cooperate with flexible feeding means.

35. 34. In a mining machine, a machine frame 40 slideable on its bottom on the mine bottom, a motor carried thereby, and feeding mechanism driven by said motor including a plural speed transmission mechanism frictionally controlled at each of its speeds and including coaxial gears rotatable on an axis extending longitudinally of the machine, a clutch member coaxial with said gears and movable horizontally in opposite directions 45 to effect different speeds, and a single terminal element through which all speeds are transmitted arranged coaxially with said gears, and a plurality of relatively rotatable feed operating and controlling members 50 driven by said transmission mechanism through said gears and each adapted to cooperate with flexible feeding means.

35. In a mining machine, a motor, and machine feeding mechanism including plural 55 speed transmission mechanism including coaxial gears rotatable on an axis extending longitudinally of the machine, a clutch member coaxial with said gears and movable horizontally in opposite directions to effect different speeds, and a single terminal element 60 through which all speeds are transmitted arranged coaxially with said gears, a feed operating member driven by said transmission mechanism and adapted to cooperate directly with flexible feeding means, and a planet- 65

ary driving connection for said feed operating member driven by said transmission mechanism.

36. In a mining machine, a motor, and machine feeding mechanism including plural speed transmission mechanism frictionally controlled at all of its speeds including coaxial gears rotatable on an axis extending longitudinally of the machine, a clutch member coaxial with said gears and movable horizontally in opposite directions to effect different speeds, and a single terminal element through which all speeds are transmitted arranged coaxially with said gears, a feed operating member driven by said transmission mechanism and adapted to cooperate directly with flexible feeding means, and a planetary driving connection for said feed operating member driven by said transmission mechanism. 70 75 80

37. In a mining machine, the combination including flexible feeding means including a plurality of flexible feeding portions extending oppositely laterally from the opposite ends of a machine during cutting across a face, rotatable members operatively engaging said portions, and mechanism for controlling the rotation of said members including a plurality of coaxial elements, a plurality of which provide coaxial portions and another of which provides orbitally moving means which constitutes a connecting means between one of said coaxial elements and one of said members, distinct operative connections between another of said coaxial elements and another of said members, and a power connection with the third coaxial element. 90 95 100

38. In a mining machine, the combination including flexible feeding means including a plurality of flexible feeding portions extending oppositely laterally from the opposite ends of a machine during cutting across a face, rotatable members operatively engaging said portions, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said coaxial elements and another of said members, means for retarding the rotation of one of said last mentioned coaxial elements, and a power connection with the third coaxial element. 110 115

39. In a mining machine, the combination including flexible feeding means including a plurality of flexible feeding portions extending oppositely laterally from the opposite ends of a machine during cutting across a face, rotatable members operatively engaging said portions, and mechanism for controlling 120 125 130

between one of said coaxial elements and one of said members, distinct operative connections between another of said coaxial elements and another of said members, means for retarding the rotation of either of said two last mentioned coaxial elements, and power connections with the third coaxial element including fast and slow speed driving connections therefor.

46. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members, and a power connection with the third coaxial element.

47. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members, and reversible power connections with the third coaxial element.

48. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means constituting a connection between said coaxial gears, operative connections between one of said coaxial elements and one of said members, distinct operative connections between another of said coaxial elements and another of said members, and fast and slow speed power connections with the third coaxial element.

49. In a mining machine, the combination including flexible feeding means including a plurality of flexible feeding portions extend-

ing oppositely laterally from the opposite ends of the machine during cutting across a face, rotatable members operatively engaging said portions, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and a power connection with the third coaxial element.

50. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and reversible power connections with the third coaxial element.

51. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and fast and slow speed power connections with the third coaxial element.

52. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial gears and the third orbitally moving gear means having teeth moving at equal angular rates constituting a connection between said coaxial gears, operative connections between one of said coaxial elements and one of said members, distinct operative connections between another of said coaxial elements and another of said members, and fast and slow speed power connections with the third coaxial element.

- angular rates constituting a connection between said coaxial gears, operative connections between one of said coaxial elements and one of said members, distinct operative 5 connections between another of said coaxial elements and another of said members, means for retarding the rotation of one of the two last mentioned coaxial elements, and a power connection with the third coaxial element.
- 10 53. In a mining machine, the combination including flexible feeding means including a plurality of flexible feeding portions extending oppositely laterally from the opposite ends of the machine during cutting across a 15 face, rotatable members operatively engaging said portions, and mechanism for controlling the rotation of said members including three coaxial elements, two providing coaxial gears and the third orbitally moving gear means 20 having teeth moving at equal angular rates constituting a connection between said coaxial gears, operative connections between one of said coaxial elements and one of said members, distinct operative connections be- 25 tween another of said coaxial elements and another of said members, means for retarding the rotation of one of the two last mentioned coaxial elements, and reversible power connections with the third coaxial element.
- 30 54. In a mining machine, the combination including flexible feeding means including a plurality of flexible feeding portions extending oppositely laterally from the opposite ends of the machine during cutting across a 35 face, rotatable members operatively engaging said portions, and mechanism for controlling the rotation of said members including three coaxial elements, two providing coaxial gears and the third orbitally moving 40 gear means having teeth moving at equal angular rates constituting a connection between said coaxial gears, operative connections between one of said coaxial elements and one of said members, distinct operative 45 connections between another of said coaxial elements and another of said members, means for retarding the rotation of one of the two last mentioned coaxial elements, and fast and slow speed power connections with the third 50 coaxial element.
55. In a mining machine, the combination including flexible feeding means including a plurality of flexible feeding portions extending oppositely laterally from the opposite 55 ends of the machine during cutting across a face, rotatable members operatively engaging said portions, and mechanism for controlling the rotation of said members including three coaxial elements, two providing coaxial 60 gears and the third orbitally moving gear means having teeth moving at equal angular rates constituting a connection between said coaxial gears, operative connections between one of said coaxial elements and one of said members, distinct operative 65 and one of said members, distinct operative
- connections between another of said coaxial elements and another of said members, means for retarding the rotation of either of said two last mentioned coaxial elements including adjustable frictional retarding means, 70 and a power connection with the third coaxial element.
56. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial 75 gears and the third orbitally moving gear means having teeth moving at equal angular rates constituting a connection between said coaxial gears, operative connections between one of said coaxial elements and one of said members, distinct operative connections between another of said coaxial elements and another of said members, means for retarding the rotation of either of said two last mentioned coaxial elements including adjustable frictional retarding means, 80 and reversible power connections with the third coaxial element.
57. In a mining machine, the combination including flexible feeding means including a plurality of flexible feeding portions extending oppositely laterally from the opposite ends of the machine during cutting across a face, rotatable members operatively engaging said portions, and mechanism for controlling the rotation of said members including three coaxial elements, two providing coaxial 85 gears and the third orbitally moving gear means having teeth moving at equal angular rates constituting a connection between said coaxial gears, operative connections between one of said coaxial elements and one of said members, distinct operative connections between another of said coaxial elements and another of said members, means for retarding the rotation of either of said two last mentioned coaxial elements including adjustable frictional retarding means, 90 and reversible power connections with the third coaxial element.
58. The combination with a mining machine of the type slidable on its bottom on the mine bottom and having cutting mechanism thereon, of a feed operating member adapted to cooperate directly with flexible feeding means, a motor, a differential operatively connected with said motor and including elements movable in an orbit upon transmission of power thereto by said motor, and driving connections between said differential and said feed operating member including a brake operative on application to retard the rotation of said operating member.
59. The combination with a mining ma- 130

chine, of cutting mechanism, feed operating mechanism including relatively rotatable feed operating and controlling members together controlling the rate of feed and the direction of said machine as a whole and means for rotating said members either simultaneously at speeds which vary in inverse ratio, or separately, including a differential including elements movable in an orbit upon transmission of power thereto by said motor, and means for driving said differential at different speeds and in different directions including a train driven from said cutting mechanism and a high speed train independent of said cutting mechanism.

60. The combination with a mining machine, of cutting mechanism, feed operating mechanism including relatively rotatable feed operating and controlling members together controlling the rate of feed and the direction of said machine as a whole and means for rotating said members either simultaneously at speeds which vary in inverse ratio, or separately, including a differential including elements movable in an orbit upon transmission of power thereto by said motor, and means for driving said differential at different speeds and in different directions including a train driven from said cutting mechanism and a high speed train independent of said cutting mechanism and a friction mechanism controlling each train.

61. The combination with a mining machine, of feed operating means thereon including a motor and a differential including elements movable in an orbit upon transmission of power thereto by said motor, worm and worm gear driving mechanism for said differential, and means driven by said motor for rotating said worm at different speeds and in different directions including a plurality of drive trains.

62. In a mining machine, the combination including flexible feeding means including a plurality of flexible feeding portions extending oppositely from the opposite ends of the machine during cutting across a face, rotatable means operatively engaging said portions, and means for controlling the rotation thereof including means operative on retardation of the rotation of one of said members to increase the speed of rotation of the other of said members automatically and proportionately.

55. In testimony whereof I affix my signature.
MORRIS P. HOLMES.
